(57) **CLAIM**

The ornamental design for a disposable component for a vaginal ultrasound therapy device, as shown and described.

DESCRIPTION

FIG. 1 is a top perspective view of a disposable component for a vaginal ultrasound therapy device.

FIG. 2 is a bottom perspective view of the component illustrated in FIG. 1.

FIG. 3 is a front view of the component of FIG. 1.

FIG. 4 is a back view of the component of FIG. 1.

FIG. 5 is a first side view of the component of FIG. 1.

FIG. 6 is a second side view of the component of FIG. 1.

FIG. 7 is a top view of the component of FIG. 1; and,

FIG. 8 is a bottom view of the component of FIG. 1.

1 Claim, 5 Drawing Sheets
